UNITED STATES PATENT OFFICE.

BENJAMIN SKIDMORE, JR., OF CHICAGO, ILLINOIS.

SUCTION AND PRESSURE CREATING APPARATUS.

1,312,588.

Specification of Letters Patent.

Patented Aug. 12, 1919.

Application filed April 6, 1918. Serial No. 227,104.

To all whom it may concern:

Be it known that I, BENJAMIN SKIDMORE, Jr., a citizen of the United States, residing at Chicago, in the county of Cook and State 5 of Illinois, have invented certain new and useful Improvements in Suction and Pressure Creating Apparatus, of which the following is a specification.

This invention relates to improvements in 10 suction and pressure creating apparatus and one of the objects of the same is to provide an improved apparatus of this character for creating a suction in a chamber or passage and which apparatus also operates to create 15 a pressure.

A further object is to provide an improved 20 apparatus of this character having means whereby the enforced circulation of a liquid will cause or create a suction or vacuum in a chamber or passage.

To the attainment of these ends and the accomplishment of other new and useful objects as will appear, the invention consists 25 in the features of novelty in substantially the construction, combination and arrangement of the several parts hereinafter more fully described and claimed and shown in the accompanying drawing illustrating this invention, and in which:

30 Figure 1 is a detail vertical sectional view of an improved apparatus of this character, constructed in accordance with the principles of this invention.

Fig. 2 is a top plan view of the parts 35 shown in Fig. 1 and with parts broken away.

Referring more particularly to the drawing, the numeral 10 designates generally a tank or receptacle within which a support 11 is rotated by means of a suitable shaft 12. 40 This support 11 is preferably hollow and is provided with a plurality of outlets opening through its periphery. The outlets are preferably in the form of nozzles 13 discharging substantially at a tangent and having an inlet 14 within the support. If desired the nozzle 13 may be reduced as at 45 15, intermediate its ends. The support is provided with a depending tubular portion 16 having an inlet 17 which is submerged

50 within the liquid 18 in the tank and communicates with a plurality of radially disposed arms or tubular passages 19 located within the hollow support 11. These arms or passages 19 may be of any desired configuration or shape and are provided with 55 reduced extremities 20 which terminate ad-

jacent the inlets 14 of the respective nozzles 13 to discharge thereinto and the exterior diameter of the arms 19 is considerably less than the diameter of the nozzle, so that when 60 the liquid is discharged from the arms or tubular members 19 by centrifugal force during the rotation of the support 11, and which support rotates above the liquid 18, a suction will be created in the hollow support 65 and through the nozzle 13 to entrain fluid therethrough and discharge the same into the tank 10 with the liquid discharged from the arms 19. When thus discharged the uncondensed fluid will rise in the tank 70 while the liquid will be precipitated. Arranged within the hollow support 11 and above the arms 19 is a partition 21, which operates with the wall of the support to form a chamber above the arms 19 and the 75 partition 21 preferably terminates short of the periphery of the support. The chamber 22 thus formed within the support has communication with a depending tubular portion 23 which extends through the tubular 80 portion 16 of the support and is of a diameter considerably smaller than the passage 16. This tubular portion 23 is journaled in a suitable bearing 24 and has communication with a passage 25 exterior of the tank 85 or receptacle 10 and in which passage it is desired to create a suction, so that when a suction is created in the chamber 22 by the discharge of the liquid by centrifugal force through the arms 19 into the nozzle, the 90 fluid in the chamber 22 and passages 23, 25 will be entrained through the nozzle. In order to prime the arms 19 to initially fill the pipes or arms 19 with the liquid 18, suitable wings or blades 26 are arranged in the 95 tubular entrance 16 of the support 11 and around the outside of the passage 23.

Thus it will be seen that when the arms or members 19 are once primed by the aid of the blades or wings 26, the liquid will be 100 thrown out of the arms 19 by centrifugal force and a strong suction will be created in the chamber 22 and passages 23, 25, when the support 11 is rotated.

What is claimed as new is:—

1. An apparatus of the character described embodying a rotatable support having a fluid passage therethrough, a nozzle at the outlet of said passage, there being a liquid passage through the support the inlet of 110 which latter passage is adjacent the axis of rotation of the support, said liquid passage

105

110

embodying a laterally extended tubular portion terminating adjacent and discharging into the nozzle to create a suction in the fluid passage when the support is rotated, and 5 means for rotating the support whereby centrifugal force will cause the liquid to be discharged through the said tubular portion of the liquid passage.

2. An apparatus of the character described 10 embodying a rotatable support having a fluid passage therethrough, a nozzle at the discharge outlet of said passage, there being a liquid passage through the support the inlet of which latter passage is adjacent the 15 axis of rotation of the support, said liquid passage embodying an extended radial portion terminating adjacent and discharging into the said nozzle, the diameter of the outlet of the said radial portion being less 20 than the diameter of the inlet of the nozzle, means for rotating the support whereby centrifugal force will cause the liquid to be discharged through the said radial portion of the liquid passage, and means for initially 25 inducing a circulation of the liquid through the liquid passage.

3. An apparatus of the character described 30 embodying a hollow rotatable support having a liquid passage therethrough, a tank within which the support rotates, said tank having liquid therein, the inlet of said passage being adjacent the axis of rotation of the support and submerged in the liquid, said passage embodying a plurality of radially 35 disposed hollow curved arms, a nozzle separate from and adjacent the outlet end of each of the arms and into which nozzles the respective arms discharge, said support also having a fluid passage therein and with 40 which fluid passage the nozzles have communication, the inlet of the fluid passage having communication with a suction passage, and means for rotating the support whereby the liquid will flow by centrifugal 45 force through the liquid passage and will be discharged therefrom and from the support through the said nozzles to create a suction in the said fluid passage.

4. An apparatus of the character described 50 embodying a hollow rotatable support having a liquid passage therethrough, a tank within which the support rotates, said tank having liquid therein, the inlet of said passage being submerged in the liquid, said passage 55 embodying a plurality of radially disposed hollow curved arms, a nozzle separate from and adjacent the end of each of the arms and into which nozzles the respective arms discharge, said support also having a 60 fluid passage through which fluid passage the nozzles have communication with a suction passage, means for rotating the support and said arms whereby the liquid in the tank will be caused to flow through the arms by 65 centrifugal force, and means adjacent the in-

let of the said liquid passage for initially inducing a circulation of the liquid through the said liquid passage.

5. An apparatus of the character described 70 embodying a rotatable hollow support embodying spaced members of comparatively large diameter, discharge nozzles opening through the periphery of the support and having communication with the interior thereof, said support having an inlet constituting with the nozzles a fluid passage through the support, said nozzles being reduced in diameter intermediate their ends, a tank having liquid therein and in which tank the said nozzles rotate above the liquid, 75 means for rotating the support, there being a liquid passage through the support separate from the said fluid passage, said liquid passage having a submerged inlet and embodying radially disposed tubular portions 80 terminating adjacent and discharging into the respective nozzles, for creating a suction in the fluid passage through the nozzles when the support is rotated, and means for rotating the support whereby the liquid in 85 the tank will be caused to flow through the said arms by centrifugal force.

6. An apparatus of the character described 90 embodying a rotatable hollow support embodying spaced members of comparatively large diameter, discharge nozzles communicating with the interior of the support and opening through the periphery thereof, said support having an inlet and constituting with the nozzles a fluid passage through the 95 support, said nozzles being reduced in diameter intermediate their ends, a tank having liquid therein and in which tank the said nozzles rotate above the liquid, there being a liquid passage through the support separate 100 from the said fluid passage, said liquid passage having a submerged inlet and embodying radially disposed tubular portions terminating adjacent and discharging into the respective nozzles, for creating a suction in 105 the fluid passage through the nozzles when the support is rotated, means for rotating the support to cause the liquid to flow through the said tubular portions by centrifugal force, and means adjacent the inlet 110 of the liquid passage for initially inducing a circulation of the liquid through the latter.

7. An apparatus of the character described 115 embodying a hollow rotatable support having one or more outlet passages opening 120 through its periphery, said support having a liquid inlet, a tank within which the support rotates, said tank having liquid therein and in which liquid the entrance of the said inlet is submerged, one or more hollow radial arms carried by the support and having communication with the said inlet of the support, the extremities of said arms terminating adjacent the respective outlets of said support, there being a fluid inlet to the sup- 125 130

- port for a fluid different from the said liquid, and means for rotating the support and arms whereby the liquid in the tank will be delivered through the arms by centrifugal force to be discharged through the respective outlets of the support to create a suction through the said fluid inlet.
8. An apparatus of the character described embodying a hollow rotatable support having one or more outlet passages opening through its periphery, said support having a liquid inlet, a tank within which the support rotates, said tank having liquid therein and in which liquid the entrance of the said inlet is submerged, one or more hollow radial arms carried by the support and having communication with the said inlet of the support, the extremities of said arms terminating adjacent the respective outlets of said support, there being a fluid inlet to the support for a fluid different from the said liquid, and means for rotating the support and arms whereby the liquid in the tank will be delivered through the arms by centrifugal force to be discharged through the respective outlets of the support to create a suction through the said fluid inlet, the said fluid inlet extending through the said liquid inlet out of communication therewith and being
9. An apparatus of the character described embodying a hollow rotatable support having one or more outlet passages opening through its periphery, said support having a liquid inlet, a tank within which the support rotates, said tank having liquid therein and in which liquid the entrance of the said inlet is submerged, one or more hollow radial arms carried by the support and having communication with the said inlet of the support, the extremities of said arms terminating adjacent the respective outlets of said support, there being a fluid inlet to the support for a fluid different from the said liquid, means for rotating the support and arms whereby the liquid in the tank will be delivered through the arms by centrifugal force to be discharged through the respective outlets of the support to create a suction through the said fluid inlet, and means adjacent the entrance of the said liquid inlet for initially inducing circulation of the liquid through the liquid passage.

In testimony whereof I have signed my name to this specification on this 3rd day of April, A. D. 1918.

BENJAMIN SKIDMORE, JR.
